UNITED STATES PATENT OFFICE

ALFONS BARNSTEINER, OF MANSFIELD, OHIO, ASSIGNOR TO WESTINGHOUSE ELECTRIC
& MANUFACTURING COMPANY, A CORPORATION OF PENNSYLVANIA

DESIGN FOR A FUEL ELECTRIC RANGE

Application filed September 20, 1930. Serial No. 37,080. Term of patent 3½ years.

To all whom it may concern:

Be it known that I, ALFONS BARNSTEINER, a citizen of the United States, residing at Mansfield, in the county of Richland and State of Ohio, have invented a new, original, and ornamental Design for Fuel Electric Range, of which the following is a specification, reference being had to the accompanying drawing, forming a part hereof, of which—

Figure 1 of the drawing is a front view

of a fuel electric range showing my new design, and

Figs 2 and 3 are end views of a fuel electric range showing my new design.

I claim:

The ornamental design for a fuel electric range substantially as shown.

In testimony whereof, I have hereunto subscribed my name this 4th day of Sept., 1930.

ALFONS BARNSTEINER.
